PULLEY BLOCK

William P. Fox, Newton Center, Mass., assignor to Merriam Bros., Inc., Boston, Mass., a corporation of Massachusetts

Application October 21, 1957, Serial No. 48,185

Term of patent 14 years

(Cl. D41—1)

FIG. 1

FIG. 2

FIG. 3

FIG. 4

Fig. 1 is a plan view of the pulley block embodying my new design;

Fig. 2 is an end elevation;

Fig. 3 is a side elevation; and

Fig. 4 is a perspective view of the design drawn to a somewhat smaller scale than the views of Figs. 1, 2 and 3.

I claim:

The ornamental design for a pulley block, as shown.
